UNITED STATES PATENT OFFICE

RAFAEL TREJO M., OF CHICAGO, ILLINOIS

PRESSING AND FOLDING MECHANISM

Application filed December 16, 1927. Serial No. 240,465.

This invention relates to mechanism for pressing and folding towels, napkins and similar flat pieces. The invention is fully described in the following specification and shown in the accompanying drawings, in 5 which:

Figure 1 is a side elevation of a machine embodying my invention;

Fig. 2 is a partial side elevation showing 10 the opposite side of the machine with part of the operating mechanism removed;

Fig. 3 is a partial enlarged view of the same showing this operating mechanism;

Fig. 4 is a view similar to Fig. 3 showing 15 the folding mechanism at the instant of making a fold in the towel;

Fig. 5 is a partial section on the line 5 of Fig. 3;

Fig. 6 is a partial enlarged section on the 20 line 6 of Fig. 5;

Fig. 7 is a partial enlarged section on the line 5 of Fig. 3;

Fig. 8 is a partial enlarged vertical section on the line 8 of Figs. 1 and 9; and

Fig. 9 is a partial side elevation showing 25 the mechanism for operating the folder.

The embodiment illustrated comprises a combined pressing and folding mechanism located upon a table 10 which is supported 30 upon suitable legs 11. The machine has two spaced side frame members 12 and 13 upon which are carried shafts 14, 15, 16 and 17 which are journalled in suitable bearings. These shafts carry drums 18, 19, 20 and 21 35 respectively which are preferably covered with cloth and which serve as pressing drums as will later be described.

This machine is driven by means of a motor 22 which has a pinion meshing with 40 a gear 23 which carries a pinion 24 which meshes with the large gear 25 which is keyed on the shaft 14. The opposite end of this shaft (Fig. 2) carries a sprocket 26 which drives a sprocket 27 keyed on the shaft 16 by 45 means of a sprocket chain 28. The shafts 15 and 17 are driven by means of a gear-train as shown in Fig. 2.

The drums 18, 19, 20 and 21 are all driven at the same surface speed. Beneath these 50 drums lies a fabric band or belt 29 which

passes over a series of rollers 30, 31, 32, 33 and 34 which turn freely so as to permit this belt to be driven by frictional contact with the various drums.

Thus it will be seen that a towel or the like 55 enters as indicated by the arrow in Fig. 1 between the drum 21 and the belt 29 will follow the path of the belt passing under the various drums and finally emerging from between the drum 18 and the roller 34.

In order to heat the drums 19, 20 and 21 60 so as to cause them to dry the towels and the like while passing beneath them, I have provided a pipe 35 which connects with a pipe 36 which leads to a boiler or other suitable source of steam supply. The pipe 36 leads to the drums 19, 20 and 21. A similar pipe 37 leads to the space beneath these drums and between the upper and lower strands of the belt 29. Suitable valves 38 and 39 control 65 the steam passing through these pipes.

The folding mechanism will now be described. The shaft 14 has a pinion 40 (Fig. 3) keyed thereon which meshes with an idler 41 which in turn meshes with a second idler 75 42 which is journalled on a stud 43 carried by the main frame 13. The idler 42 carries a series of intermittent gear sectors 44 which are secured to the side of the idler 42. These sectors mesh with a gear 45 keyed on a shaft 80 46 which is suitably journalled in the main frame 13. This shaft 46 carries a rocker arm 47 which is pivotally connected through a link 48 with a plate or frame 49 which is pivotally connected to the table 10 at the hinge point 50. The plate or frame 49 is normally drawn back by a suitable spring 51.

As shown in Fig. 3, one of the gear sectors 44 is just beginning to engage the gear 45 thereby driving it forward and causing the 90 arm 47 to move thereby forcing the frame 49 to the right. This action continues as shown in Fig. 4 until the frame 49 lies flat upon the top of the table 10 thereby carrying forward the towel A as it emerges from beneath 95 the drum 18 and giving a fold A¹.

The mechanism is holding this fold while the frame 49 returns. The shaft 46 carries a gear segment 52 which meshes with a gear-rack 53. The latter passes over a spring 54 100

and carries a short section or rack 55 which meshes with an interrupted gear 56. This gear is carried on a shaft 57 which is journaled in suitable bearings carried by the table 10. The shaft 57 carries an arm 58 (Fig. 4) which in turn carries a foot 59 which serves as a means for holding the forward edge of the towel fold A¹. In order to permit the oscillating frame 49 to pass out from under the foot 59, I have provided the frame 49 with a yieldable member 60 which is pivotally connected thereto by hinges 61 and which is normally held in substantially the same plane by means of a spring or the like 62, and whose construction will be explained later.

As the plate or frame 49 descends the gear 52 draws the rack 53 through suitable guides until the rack section 55 engages the teeth of the interrupted gear 56 thereby lifting the arm 58 and the foot 59. Thus as the frame 49 descends, the foot 59 is raised to the dotted line position of Fig. 4. As the short gear section 55 passes beneath the gear 56, the foot 59 falls of its own weight until it assumes the full line position of Fig. 4 so as to rest upon the top of any fold of the towel A¹ or the like.

By this time the gear sector 44 has passed the gear 45 and the spring 51 throws the parts back to the position shown in Fig. 3. The oscillations of the frame 49 are so timed that they lay the towel A in a series of flat folds A¹ with one fold over the other until the entire towel has been thus laid with a series of transverse folds one over the other. The plate 49 has a yieldable strip 60 secured at its outer edge by means of hinges 61. This strip is normally held up in the full line position shown in Fig. 6 by means of springs 62 at the hinge points. This provides a yieldable edge so that the plate 49 can be withdrawn from beneath the foot 59.

As the gear-rack 53 is drawn by means of the gear-segment 52 to the left, the short section, or rack, 55 engages the gear 56 thereby actuating the arm 58. At the end of the movement to the left, the gear 45 passes out of engagement with the gear sectors 44 and permits the gear-segment 52 to rotate in the opposite direction and permits the gear-rack 53 to be returned to a position at the right by means of the spring 54, or any other suitable means.

It will be observed that the missing teeth in the interrupted gear 56 permits the gear-rack 53 to be retracted to a position on the right without engaging the gear 56.

The mechanism for folding the towel about its axis extending longitudinally of its movement will now be described. The motor 22 drives the gear 63 which is keyed on the shaft 64 which is journaled beneath the table 10 in suitable bearings. It carries a bevel gear 64^a which meshes with a gear 65 on the shaft 66 which is likewise journaled beneath the table 10. This shaft carries a roller

67 about which passes a belt 68 which passes under a tightening roller 69 as shown in Figs. 5 and 7. The belt 68 extends to one side of the machine and serves to convey the towels, napkins and the like after they have been folded as will later be described.

The shaft 66 carries a friction wheel 70 which is continuously driven by the motor 22. A friction wheel 71 (Fig. 8) is keyed on a shaft 72 and carries a gear sector 73 which meshes with a similar gear sector 74 on the shaft 75. The shafts 72 and 75 are parallel to each other and lie near the top of the table 10 as shown in Fig. 7. These shafts are normally in the position shown in Figs. 5 and 8.

The shaft 75 carries a leaf 76 of sheet metal or the like, the leaf being normally retained in position as shown in Fig. 5 by a spring 77 coiled about the shaft 75. The shaft 72 is provided with a similar leaf 78 which is normally held in the position shown in Fig. 5 by the coil spring 79. The leaf 78 has an extension 80 lying at right angles thereto whose purpose will later be explained.

A transversely disposed shaft 81 is controlled by means of a lever 82 as shown in Fig. 1 which is at the side of the machine and under the control of the operator. If desired this may be controlled by a treadle instead of a hand-lever. The shaft 81 carries a suitable axle 82^a upon which is journaled a friction wheel 83. As shown in Fig. 8 this friction wheel is normally out of contact with both the friction wheels 70 and 71, but by rocking the shaft 81 the friction wheel 83 is brought into frictional engagement with the friction wheels 70 and 71 so that it serves to transmit power from the wheel 70 to the wheel 71. When this occurs the shaft 72 is turned clockwise as viewed in Figs. 5 and 8, while the shaft 75 is turned in a counter-clockwise direction.

It will be understood that the folding of towels, napkins and the like, as has previously been described, takes place upon the leaves 76 and 78. The actuation therefore by the operator of the shafts 72 and 75 causes the leaves 76 and 78 to fold toward each other thereby causing the towel to assume the position A² of Fig. 7.

At the same time the extension 80 of the leaf 78 forces the central part of the towel through the opening 84 in the plate 85. The towel is then caught between the belt 68 and the roller 69 which are then continuously in operation so that the towel is drawn through between the belt and the roller thus completing the fold of the towel and carrying it to the side of the machine where it is dried upon a suitable table or the like.

The operator pulls the lever 82 only long enough to cause the fold to be made. Should he hold it longer, however, than just enough to cause the leaves 76 and 78 to move to the position shown in Fig. 7, slippage will occur between the roller 83 and the friction wheel 70.

In order to prevent the shaft 81 being actuated to cause this last folding operation taking place while the plate 49 is in other than the retracted position shown in Fig. 3, I have 5 provided the shaft 81 with a control-arm 86 as shown in Fig. 9, which has a shoe 87 which operates on the gear 42. So long as the gear 42 is in a position which insures the plate 49 being retracted as indicated, the shoe 87 will 10 rest on the gear 42. When, however, one of the gear sectors 44 is not meshing with the gear 45, another of the gear sectors 44 will fall beneath the shoe 87 thereby preventing the shaft 81 being moved to a position which 15 will cause the friction roller 83 being brought into engagement with the friction wheels 70 and 71. Thus it will be seen that it is impossible to actuate this last folding mechanism while the plate 49 is in other than the re- 20 tracted position.

While I have shown and described but a single embodiment of this invention, it is to be understood that it is capable of many modifications. Changes therefore in the construction 25 and arrangement may be made which do not depart from the spirit and scope of the invention as disclosed in the appended claims.

I claim:

1. In a folding mechanism, means for 30 transversely folding a towel, leaves adapted to receive said folded towels, said leaves being hinged about axes extending longitudinally of the machine and means actuating said leaves and serving to fold the ends 35 of said towel inwardly.

2. In a folding mechanism, means for 40 transversely folding a towel, leaves adapted to receive said folded towels, said leaves being hinged about axes extending longitudinally of the machine for folding the ends 45 of said towel inwardly, said leaves being spaced apart and having an opening therebetween through which the towel may pass, one of said leaves having a flange adapted to force said towel through said opening.

3. In a folding mechanism, means for 50 transversely folding a towel, leaves adapted to receive said folded towels, said leaves being hinged about axes extending longitudinally of the machine for folding the ends 55 of said towel inwardly, said leaves being spaced apart and having an opening therebetween through which the towel may pass, one of said leaves having a flange adapted to force said towel through said opening, and a belt conveyor beneath said opening adapted to carry said folded towel to one side of the machine.

4. In a device of the character set forth, 60 means for folding towels transversely and means for folding said towels longitudinally, including an oscillating member lying in the path of said towel, and means for holding the forward edge of the folded towel while the 65 oscillating member returns.

5. In a device of the character set forth, means for folding towels transversely, means for folding towels longitudinally, including an oscillating member lying in the path of said towel, means for holding the forward edge of the folded towel while the oscillating member returns, and a yieldable forward edge on said member. 70

6. In a device of the character set forth, means for folding towels transversely, means for folding said towels longitudinally, including an oscillating member lying in the path of a towel, a yieldable forward edge on said member, and an arm adapted to overlie said forward edge when at the most forward 80 part of its swing to grip a towel folded thereon.

In testimony whereof I have hereunto set my hand this 9th day of December, 1927.
